WINDOW SASH AND SCREEN

Filed Dec. 17, 1928

UNITED STATES PATENT OFFICE

OSCAR R. HANKINS, OF AURORA, ILLINOIS, ASSIGNOR TO THE LARIMER COMPANY, OF AURORA, ILLINOIS, A CORPORATION OF ILLINOIS

WINDOW SASH AND SCREEN

Application filed December 17, 1928. Serial No. 326,649.

This invention relates to a window and screen construction, and is particularly concerned with a novel construction of screen and frame therefor which may be detachably connected to a metal window frame so as to cover the opening therein, permitting admission of air but excluding insects and the like.

The invention is directed to many novel details of construction and arrangements of parts for providing a novel construction of screen member and also for effectively providing for its ready connection to or removal from the window frame on which it is to be mounted.

15 An understanding of the invention may be had from the following description taken in connection with the accompanying drawing, in which,

Fig. 1 is a front elevation illustrating the screen connected to the window.

Fig. 2 is an end elevation of the structure shown in Fig. 1.

Fig. 3 is a view similar to that shown in Fig. 2 showing the screen detached from the window, and,

Figs. 4 and 5 are somewhat enlarged sections on the planes of lines 4-4 and 5-5, respectively, of Fig. 1.

Like reference characters refer to like parts in the different figures of the drawing.

The window frame 1 is of metal preferably, and may be made in accordance with any preferred construction, and in practice at its outer side includes upper and lower vertical flanges 2 and 3. Lengthwise of the upper flange 2 and on its outer face above the opening in the frame, a retaining member 4 in the form of a flat bar of metal having an outwardly off-set lower section is permanently secured as by spot welding or otherwise. Other retaining members or keepers 5, each having an upper outwardly off-set section are secured to the outer faces of flanges 6 on the vertical sides of the frame 1, said flanges 6 being in the same vertical plane as the flanges 2 and 3 previously described.

The screen frame which is to be applied to the window against the flanges 2, 3 and 6 has upper and lower parallel sides spaced

from each other and similar vertical ends. The material from which the screen frame is made is angle iron with legs 7 and 8 located at right angles to each other, it being understood that the upper and lower sides and the end members of the frame are rigidly connected together at the corners of the frame by welding. The legs 7 of the angle bars which are used in making the screen frame extend outwardly and are adapted to come against the outer sides of the flanges 2, 3, and 6 of the window frame when the screen is attached thereto. In applying the screen frame to the window frame the flange 7 at the upper side of the window frame is introduced underneath the retaining member 4 and then the screen frame is brought against the outer sides of said flanges 2, 3 and 6 of the window frame, suitable recessed portions or notches 9 being cut in the edges of the legs 7 of the vertical members of said screen frame so as not to interfere with the application of the screen frame to the window, the keepers 5 and the latches on the screen frame to engage therewith necessitating the recesses 75 9 in the vertical sides of the screen frame.

At the inner side of each of the recesses 9 described a flat bar 10 is permanently secured, of the form shown, and extending outwardly from the legs 7 of the vertical end members of the screen frame to which they are connected. On each of the bars 10 a latch member 11 is pivotally mounted at 12, one end thereof being turned substantially at right angles and terminating in a latching ear 13, and the other being turned in the opposite direction and terminating in a second ear 14 for engagement by the fingers of the operator to turn the latch bars. When the screen frame has been applied to the window frame the latching bars 11 may be turned from the position shown in Fig. 3 to that shown in Fig. 2, whereupon the ears 13 come back of and engage with the keepers 5, securely latching the screen frame in place; but by turning the latching bars 11 back to the position shown in Fig. 3, release of the latches from the keepers 5 is very quickly and easily obtained and the screen frame may be removed from the window.

dow frame when the unlatching has been accomplished.

The screen mesh 15 is attached to the screen frame in a very effective and novel manner. 5 The screen is cut to a size slightly larger than the opening through the screen frame, is laid over said opening with the edge portions thereof coming against the free edges of the outwardly extending legs 8 of the angle bar 10 sides and ends making up the screen frame, and the edge portions of the screen mesh are turned to lie against the outer sides of said legs 8. A sheet metal U-shaped clip 16 is placed over the outer free edge of each of the 15 legs 8. Each of the U-shaped clips has an inner leg 16a and an outer longer leg 16b, and when the clips are applied to the side and end members of the screen carrying frame the screen is stretched and tightened and the 20 edge portions thereof bent to lie against the outer sides of said legs 8 while the outer longer legs 16b of the securing clips completely cover the edge portions of the screen mesh.

Each of the outwardly extending legs 8 of 25 the sides and end members of the screen frame are formed with a plurality of openings 17 therethrough spaced apart desired distances. After the screen mesh is attached and the U-shaped clips 16 applied thereto, the outer legs 30 16b of said clips are dented inwardly, as indicated at 18, at said openings 17 thereby making a sufficiently secure connection of the retaining sheet metal U-shaped clips to the screen frame that the screen will not disconnect therefrom.

Should the screen become rusted, torn, or 35 injured or otherwise require replacement this may be very easily done as the U-shaped retaining clips may be removed by springing the outer legs 16b away from the legs 8 of the 40 frame members, whereupon the clips and the old screen mesh can be removed, a new screen mesh put in place of the old and the clips re-applied; or if the old securing clips are 45 injured in this process they may be replaced with new, attaching in the same way as the old were previously attached. This construction permits ready replacement of the screen mesh without the employment of 50 skilled labor.

The invention described is very practical and serviceable and has proved its value in actual practice. The appended claims define the invention which is to be considered comprehensive of all forms of structure coming 55 within their scope.

I claim:

1. In a window screen, a frame made of angular members having two flanges at right 60 angles to each other, a screen mesh covering said frame and extending adjacent the outward extending flanges thereof, U-shaped clips clamped over the said outward extending flanges and over the screen mesh adjacent 65 thereto, each of said outward extending

flanges having openings over which said U-shaped clips extend and indentations in said clips entering said openings.

2. In a window screen, a frame made of angular members having two flanges at right 70 angles to each other, a screen mesh covering said frame and extending adjacent the outward extending flanges thereof, U-shaped clips clamped over the said outward extending flanges and over the screen mesh adjacent 75 thereto, each of said outward extending flanges having openings over which said U-shaped clips and said screen mesh extend and indentations in said clips and screen mesh entering said openings.

3. A window screen comprising a frame made of members having elongated cross sections axially with respect to the screen, a screen mesh covering said frame and extending adjacent the elongated portions, U-shaped 85 clips clamped over the elongated portions of the members and over the screen mesh adjacent thereto, each of said elongated portions having openings over which said U-shaped 90 clips extend and indentations in said clips entering said openings.

In testimony whereof I affix my signature.
OSCAR R. HANKINS.
